Primary Examiner—Antoine D Davis(74) *Attorney, Agent, or Firm*—Knobbe, Martens, Olson & Bear LLP(57) **CLAIM**

The ornamental design for a portable coordinate measurement machine, as shown and described.

DESCRIPTION

FIG. 1 is a perspective view of a portable coordinate measurement machine showing our new design in accordance with a first embodiment of the invention;

FIG. 2 is a side view thereof;

FIG. 3 is a front view thereof;

FIG. 4 is a rear view thereof;

FIG. 5 is a top view thereof; and,

FIG. 6 is a bottom view thereof.

A single side view is provided for each embodiment of portable coordinate measurement machine as the opposite side is symmetric.
